UNITED STATES PATENT OFFICE.

HENRY C. WEEDEN, OF BOSTON, MASSACHUSETTS.

PIPE-JOINT.

SPECIFICATION forming part of Letters Patent No. 766,855, dated August 9, 1904.

Application filed April 18, 1904. Serial No. 203,805. (No model.)

To all whom it may concern:

Be it known that I, HENRY C. WEEDEN, a citizen of the United States, residing at Boston, in the county of Suffolk and State of Massachusetts, have invented certain new and useful Improvements in Pipe-Joints, of which the following is a specification.

My invention relates to improvements in pipe-joints of the type for which I have filed application, Serial No. 151,604, for Letters Patent; and its object is to make these joints more efficient, particularly where the sections composing the joints are for any reason limited in depth.

15 I have found that the form of pipe-joint described in my above-named application for patent is thoroughly efficient for all sizes of soil, water, and gas pipe where the necessary depth of hub can be obtained. My present improvement relates to a change in the construction of the sectional joint-forming ring whereby it will make a tight joint even when used with a comparatively slight depth of hub.

In the accompanying drawings I have shown 25 at Figure 1 in longitudinal section a joint in which my present invention is employed; at Fig. 2, a horizontal section on the central line of Fig. 1; at Fig. 3, a vertical section of one of the sections of a joint member embodying 30 my present improvement, and at Fig. 4 two members of said joint shown in perspective and slightly separated.

I have found in practice that when the members of a joint-ring are made of plain iron,

which is the material most commonly employed, and where only a relatively small depth for the ring can be allowed—for example, a depth of one inch upon the hub of a ten-inch pipe—that a tight joint is not always obtained. By my present improvement this difficulty is overcome. I form the sections of my joint-ring with a center or core of iron A and coat this externally, particularly upon those portions which are to come into contact with the hub and spigot of the pipe to be joined, with a covering B, of softer or more compressible metal. This covering may be of a single metal, such as copper or tin or zinc, or of an alloy of metals, which alloy shall be compressible as compared with the iron center. By this construction I find that I may use a ring of relatively slight depth and still be enabled to obtain a tight joint under circumstances where a ring of plain iron would not be tight.

55 I claim—

A pipe-joint ring-section of the character described, formed of an iron core and covered upon its outer and inner faces with a relatively compressible metal or combination of metals.

In testimony whereof I have hereunto subscribed my name this 16th day of April, 1904.

HENRY C. WEEDEN.
